UNITED STATES PATENT OFFICE

GLENN J. BARRETT, OF CHICAGO, ILLINOIS, ASSIGNOR TO PORTABLE ADDING MACHINE COMPANY, OF CHICAGO, ILLINOIS

LOCKING DEVICE FOR ADDING-MACHINE CASES

Application filed December 24, 1928. Serial No. 328,256.

My invention relates to improvements in locking devices for hinged adding machine cases.

The objects of the invention are:

5 First, to provide a common means for locking both the lid or cover in position and also for locking the totaling means when desired.

Second, to provide a greatly simplified construction eliminating many of the ordinary 10 features of a key operated lock and provide a lock not readily manipulated without the key.

The invention is pointed out in the claims.

A structure illustrating the same is clearly 15 shown in the accompanying drawings, in which:

Fig. 1 is a perspective view of the adding machine enclosed in a suitable case.

Fig. 2 is a partial detail top view of the 20 total buttons of the adding machine and the actuating portion of the lock, the catch or bolt being on dotted lines.

Fig. 3 is a sectional view of the lock on line 3—3 of Fig. 2, showing its relation to 25 the totaling lever of the adding machine.

Fig. 4 is a detail of the lock bolt or latch.

The parts will be identified by their numerals of reference which are the same in all the views.

30 This invention may be adapted to any adding or calculating machine having an enclosed case with a hinged or removable cover portion for inspecting the adding portion of the machine, insertion of paper and the like.

35 I have shown my device as applied, for example, to the Corona adding machine. This machine is sometimes sold in combination with a cash drawer and is used to record business operations.

40 When used in this connection it is highly desirable to lock the hinged portion so that it cannot be raised and the record on the tape inspected by others than the proprietor or authorized person. It is also desirable to lock the totaling devices at the same time so that the machine cannot be cleared until the proprietor desires to do so. To this end I have provided structures which I will now describe.

45 Fig. 1 shows the adding machine which

may be of almost any pattern, but for convenience I have shown the Corona adding machine, enclosed in a case consisting of the forward portion 1 which is permanently attached to the machine, and the rear cover 53 portion 2 which is preferably hinged at the rear to the portion 1, and adapted to tilt backwardly to expose the rear portion of the adding machine, paper roll and other parts.

This case, comprising base part 1 and cover 63 2, completely encloses the machine, there being no opening for the paper or tape when used in connection with a cash drawer which, however, is not a part of this invention and is not shown.

Adding machines of the class of the Corona have a total button or key and also a subtotal button or key, the operation of which is well understood in the art. In Fig. 2 the total button 3 is carried by the total lever 4. It 73 will be understood that operation of the machine with this button 3 pushed back, prints the total upon the tape and at the same time leaves the machine clear.

The sub-total button 5 is mounted on lever 6, the action of which is understood. Operation of the adding machine with this button pushed back produces what is known as a subtotal upon the tape but does not clear the machine. Both of these operations are well understood in the art.

At a point upon the lid 2 just back of the location of the total and sub-total buttons just referred to, is located the actuating portion of my lock. The stud 7 bearing the 85 beveled head 8 extends through the lid at this point through a proper bearing or guide sleeve 71. The upper portion or head of this stud is beveled so that it is inconvenient and practically impossible to apply a wrench or pliers to turn the same. In this beveled portion I have placed two notches 9 into which the prongs of a special key 10, or spanner wrench, may be fitted and by means of this key, the stud 7 turned into locking position.

The lower portion of this stud 7 is provided with a squared projection and a threaded end. The locking arm or bolt 11 is placed upon this squared end of 7 and held in position by the nut 12. 13 is a spring washer

placed above the arm 11 and exerts a tension between the arm 11 and the bearing for the stud 7. The object of this spring washer is to provide enough friction to require some little power to turn the stud 7 so that it will be difficult to turn same without a key.

The case is divided as shown in Fig. 1 the rear portion being hinged and adapted to turn back upon said hinge. When the cover 10 is in normal position, as shown, by the use of the key 10 the lock arm or bolt 11 may be turned toward the front portion of the case until the forward end of the arm 11 passes under a lip 14 upon the main portion 1 of the 15 case. When the forward end of 11 is engaged under this lip 14, as described, it is impossible to raise the lid 2.

However, a notch 15 is provided upon said arm 11 at a point where it will block any 20 operative movement of the arm 6 when said arm 11 is moved into position shown by dotted lines in Fig. 2. When in this position this arm 11 locks the sub-total lever 6. Said arm 11 is also provided with another notch 16 25 which is adapted to block the total lever 4 at the same time notch 15 blocks the sub-total lever 6. Thus the cover can be locked and at the same time the total and sub-total levers be left free; or the cover and sub-total 30 lever can be locked and the total lever left free. If desired, complete actuation locks all the parts.

Having thus described my invention, what I claim as new and desire to secure by Letters 35 Patent, is:

1. In combination with an adding machine having an enclosing case with cover section pivotally mounted thereon and having total and sub-total levers mounted near the junction of said sections, of a locking bolt arm 40 pivotally mounted in one of said sections near said junction of said sections, said locking arm having an extension adapted to have locking engagement with the other of said 45 sections of said case, when partially turned toward an extreme position, means carried by said locking arm for locking said total and sub-total levers when said locking arm is turned to its limit of locking movement, a 50 pivotal extension from said locking arm through said case, bearing a head with beveled edges, notches in said beveled head, a removable key to cooperate with said notches in said beveled head, and a friction means adapt- 55 ed to exert a friction tension upon said locking arm.

2. In combination with an adding machine having an enclosing case with cover section pivotally mounted thereon, and having total 60 and sub-total levers mounted near the junction of said sections, of a locking bolt arm pivotally mounted in one of said sections near said junction of said sections, said locking arm having an extension adapted to have 65 locking engagement with the other of said

sections of said case when partially turned toward an extreme position, means carried by said locking arm for locking said total and sub-total levers when said locking arm is turned to its limit of locking movement, a pivotal extension from said locking arm through said case bearing a head with beveled edges, notches in said beveled head, and a removable key to cooperate with said notches in said beveled head.

3. In combination with an adding machine having an enclosing case with cover section and total and sub-total levers, of a movable locking means carried by one of said sections of said enclosing case, a locking portion carried by said movable locking means adapted to have locking engagement with the other of said sections of said case when only partially moved into an extreme position, and means carried by said main locking means 85 for also locking said total and sub-total levers when said main locking means is moved to the limit of its locking position.

In witness whereof I have hereunto set my hand.

GLENN J. BARRETT.
